UNITED STATES PATENT OFFICE

WILLIS O. PROUTY, OF HERMOSA BEACH, CALIFORNIA, ASSIGNOR TO METLOX CORPORATION, LTD., OF MANHATTAN BEACH, CALIFORNIA, A CORPORATION OF CALIFORNIA

DESIGN FOR A MEDICINAL RADIANT DEVICE

Application filed February 19, 1932. Serial No. 42,936. Term of patent 14 years.

To all whom it may concern:

Be it known that I, WILLIS O. PROUTY, a citizen of the United States and a resident of the city of Hermosa Beach, county of Los Angeles, and State of California, have invented a new, original and ornamental Design for a Medicinal Radiant Device, of which the following is a specification, reference being had to the accompanying drawing, forming part thereof, in which:

Figure 1 is a front elevation of a medicinal radiant device embodying my invention; and

Fig. 2 is a side elevation thereof.

The dominant features of the design are the configuration of the casing for accommodating the radiant element, and the handle of the casing.

I claim:

The ornamental design for a medicinal radiant device substantially as shown and described.

WILLIS O. PROUTY.
